UNITED STATES PATENT OFFICE.

HARRY L. TANNER, OF BROOKLYN, NEW YORK, ASSIGNOR TO FORD INSTRUMENT COMPANY, INC., OF LONG ISLAND CITY, NEW YORK, A CORPORATION OF NEW YORK.

SPEED-REGULATING MECHANISM.

Application filed September 14, 1927. Serial No. 219,548.

This invention relates to speed regulating mechanism and is in the nature of an improvement on the apparatus disclosed and claimed in the patent to Hannibal C. Ford, No. 5 1,577,618, March 23, 1926.

According to the disclosure of said patent, the speed regulation is attained by employing an epicyclic gear train to one member of which the prime mover is connected, while to 10 the second member of the train a speed limiting device, such as an escapement, is connected. In order that the speed limiting device may be driven there is connected to the third member of the gear train a device for applying a constant torque thereto against which the speed limiting device reacts. The arrangement is such that for a particular speed of the prime mover, as determined by the 15 characteristics of the apparatus, there will be no movement of the third member with respect to the first and second members of the gear train, but if the speed of the prime mover differs from such particular speed there will be a relative movement of the third member 20 which is utilized for actuating a contact device for altering the speed of the prime mover by a suitable control system, for example, an electrical system.

In said patent the torque is applied to the 30 third member of the gear train by means of a spring acting on a lever adapted to bear against a cam connected to the third member but which may move with respect to the lever when there is any movement of this third 35 member due to variations in speed of the prime mover. Such movement of the cam actuates a part of a contact device to cause a change in the speed of the prime mover through the electrical control system. The 40 contact device normally short-circuits a resistance in the motor circuit and when the contact is broken the current through the motor circuit is reduced and the speed of the motor drops. This will cause the third member 45 of the epicyclic gear train to turn in the opposite direction and thereby actuate the contact device to cause an opposite change in the speed of the motor or prime mover. The speed of the prime mover will therefore be 50 closely regulated and the movable part of the contact device will be continually oscillating to effect regulation of the prime mover through the electrical control system. If for any reason the increasing speed of the prime 55 mover is not checked by the control system

the third member of the gear train may, without injury to the apparatus, continue to turn carrying with it the cam against which the lever bears and cause successive opening and closing of the contact device.

One of the principal objects of the present invention is to provide novel and advantageous means of simple and inexpensive construction for regulating the speed of a prime mover.

Other objects involve the use of novel means for varying the supply of energy to the prime mover, means for varying the resistance in a control circuit of a prime mover, and novel means for preventing damage to 70 the apparatus when the prime mover does not respond quickly enough to the action of the regulatory means.

According to the present invention, the speed regulation may be obtained, advantageously by means of a resistance element in a control circuit and means operated by the third member of the epicyclic gear train for varying the resistance of said element to increase or decrease the resistance in accordance with variation of the speed of the prime mover above or below the predetermined speed. Means for limiting the operation of the resistance varying means are provided and this means is so connected with the third 80 member of the gear train that the connection will yield but will tend to maintain the adjustment of the resistance element until the prime mover responds to the influence of the control system and the third member of the 85 epicyclic gear train is turned in the opposite direction.

A further object of the invention relates to means for effecting gradual variation of resistance in a control circuit, thereby preventing 90 arcing of contacts.

The particular nature of the invention together with other objects and advantages thereof will appear more clearly upon consideration of the following description and 100 the accompanying drawings in which—

Fig. 1 is a simplified diagram of an arrangement for controlling an electric motor in which an escapement is used in the speed limiting device;

Fig. 2 is a detail view partly in section of a yielding connection between the third member of the gear train and the electric control system, and

Fig. 3 is a view of a modified form of device 110

for varying the resistance in the electrical control system.

Referring to Fig. 1, 10 represents collectively an epicyclic gear train of the bevel type consisting of a first member or gear 11, a second member or gear 12, and a third member 13 which is in the form of a pair of gears meshing with gears 11 and 12 and mounted upon a spider 14 attached to a shaft 15 upon which the first and second gears 11 and 12 respectively are loosely mounted in accordance with the usual construction of this particular type of epicyclic gear train.

The first member 11 is provided with a gear 16 meshing with a worm 17 on a shaft 18 connected with the prime mover, the speed of which is to be regulated. For purposes of illustration the prime mover has been shown as an electric motor 19 provided with an armature 20 and a shunt field 21. The motor is supplied with current by mains 22 in one of which is inserted a resistance 23 such as a carbon pile having a fixed end plate 26 and a movable end plate 27. By varying the pressure on the plate 27 towards the plate 26 25 the resistance of the pile 23 may be varied to produce the desired change in the armature current for regulating the speed of rotation of the armature. The pressure of the plate 27 towards the plate 26 30 may be controlled by means to be described hereinafter. The second member 12 of the epicyclic gear train is provided with a gear 28 which through a gear 29 and pinion 30 is connected with an escapement 31 which may 35 be of any suitable construction and is here shown as consisting of an escape wheel 32, pallet 33, fork 34, balance wheel 35 and spring 36.

The shaft 15 of the third member 13 of the epicyclic gear train has an enlarged end 37 against which a gear or pinion 38 is pressed by means of a helical spring 39 interposed between the pinion 38 and a member or disc 40 on a pin 41 which passes through the spring 39 and the pinion 38 into an opening 42 in the head 37 being secured to the head in any suitable manner as by a pin 43. Meshing with the pinion 38 is a sector 44 carried by an arm 45 fixed on a shaft 46 which also has fixed 40 thereon an arm 47. Pivoted to the arm 47 is a rod 48 passing loosely through a fixed member 49 and also pivoted to one arm of a lever structure or lever 50 of which the other arm forms with a link 51 a toggle by which pressure may be exerted on the movable plate 27 of the carbon pile 23, by means of a member 52 pivoted to link 51 and mechanically connected with the plate 27 but insulated therefrom by insulating material 53. Mounted 55 on the rod or link 48 is a spring 54 interposed between the member 49 and a collar 55 fixed on the rod 48. The spring 54 urges the rod 48 in a direction to straighten the toggle including the link 51 and the adjacent arm of 60 the lever 50 and thereby exerts pressure on

the carbon pile 23. Excessive movement of the parts connecting the pinion 38 with the movable plate 27, which might result from continuous rotation of shaft 15 in one direction, is prevented by two stops 56 arranged 70 on opposite sides of the arm 45, slippage occurring at the connection between the pinion 38 and the enlarged end of the shaft 15 as soon as the arm 45 strikes one of said stops 56.

In considering the operation of the simplified form of apparatus shown in Fig. 1, let it be assumed that the conditions are substantially as indicated in said figure, that is, with the plate 27 pressed towards the fixed plate 26 by means including the spring 54 80 so that the resistance of the carbon pile 23 is such as to permit a flow of sufficient current to drive the motor 19 at the desired or at a greater speed. The spring 54 will, acting through the rod 48 and other connections including the pinion 38, apply a torque to the third member 13 of the epicyclic gear train so that as the first member 11 is rotated by the motor 19, the third and second members 13 and 12 respectively, will also be rotated to 90 drive the escapement through gears 28 and 29 and pinion 30. If the motor drives the first member faster than the member 12 is driven under control of the escapement, the third member 13 will be driven relatively to the 95 second member 12 in a direction to compress the spring 54, thereby actuating toggle 50, 51 and reducing the pressure on the plate 27 and increasing the resistance of the resistance element or carbon pile 23. This has the effect of reducing the current through the armature 20 and of reducing the speed of the motor. As soon as the speed of the motor is reduced to such an extent that the first member 11 turns at a slower rate than the second 105 member 12, the third member will begin to turn in the opposite direction and permit the spring 54 to expand and operate the toggle 50, 51 to increase the pressure on the resistance element 23, thereby decreasing the resistance and causing a greater flow of current through the armature 20 and an increase of 110 speed of the motor.

The use of a suitably designed toggle structure enables variable pressure on the carbon 115 pile 23 to be obtained with a substantially uniform torque on shaft 15 of differential 10. This effect is obtained due to the fact that as the pressure on the movable plate 27 of the carbon pile is increased the toggle 50, 51 is 120 straightened and for a given torque on the shaft 15 a much greater pressure on the plate 27 is exerted than would be the case with the toggle bent to a greater extent.

The apparatus is so designed that when the 125 resistance of the element 23 is reduced to a certain extent in the operation of the apparatus, the motor will tend to run above the predetermined speed at which it will drive the escapement without any movement of the 130

third member of the epicyclic gear train about the axis of its shaft 15. Also when the resistance is increased due to excessive speed of the motor, the tendency will be to 5 reduce the speed of the motor below said predetermined speed. These operations will be repeated in sequence continually with the result that the speed of the motor will be maintained substantially constant except for such 10 variations as take place before the change of speed is checked by the reduction or increase of the resistance of the resistance unit or carbon pile 23 in the motor circuit.

As illustrated in Fig. 3, the resistance unit 15 in the motor circuit may be in the form of a rheostat 57 including an arm 58 mounted to swing about a pivot 59 and be brought into contact with any one of a series of contacts 60, thereby varying the resistance in the motor circuit. The arm may be operatively connected with the rod or link 48 of Fig. 1 by means of an arm 61 pivotally connected with said rod 48 and rigidly connected with said arm 58 adjacent said pivot 59, suitable 25 insulation of the parts being obtained by use of insulating material 62. It will be evident that the rheostat shown in Fig. 3 may be used in the same general manner as the resistance unit 23 of Fig. 1 to control the action of 30 a prime mover.

It should be understood that various changes in the arrangement of the apparatus and in details of construction may be made without departing from the true spirit and 35 scope of the invention.

Having thus described my invention, I claim:

1. In speed regulating apparatus, a prime mover, an electrical speed control system for 40 said prime mover including a control circuit and a variable resistance element in said circuit, said speed control system being adapted to control the speed of said prime mover in accordance with the variation of the resistance 45 element, an epicyclic gear train to one member of which the prime mover is connected, speed limiting means connected to another member of the gear train, and means for controlling said variable resistance element including a pinion having a yielding connection with a third member of the gear train, a member connected with said pinion for actuation thereby, and a spring associated with the member for moving it to vary the resistance of the resistance 55 element.

2. In speed regulating apparatus, a prime mover, an electrical speed control system for 60 said prime mover including a control circuit and a pressure-controlled variable resistance element in said circuit, said speed control system being adapted to control the speed of said prime mover in accordance with the variation of the resistance of said resistance element, an epicyclic gear train to one member 65 of which the prime mover is connected,

which the prime mover is connected, speed limiting means connected to another member of the gear, and means for varying the pressure on said resistance element including a toggle acting thereon and means for actuating said toggle including a yieldable connection with a third member of the gear train. 70

3. In speed regulating apparatus, a prime mover, an electrical speed control system for 75 said prime mover including a control circuit and a pressure-controlled variable resistance element in said circuit, said speed control system being adapted to control the speed of said prime mover in accordance with the variation of the resistance of said resistance element, an epicyclic gear train to one member of which the prime mover is connected, speed limiting means connected to another member of the gear, and means for varying the pressure on said resistance unit including a toggle, a spring tending to actuate said toggle to vary the pressure, and means actuated by a third member of the gear train for controlling said toggle. 80 85

4. In speed regulating apparatus, a prime mover, an electrical speed control system for 90 said prime mover including a control circuit and a pressure-controlled variable resistance element in said circuit, said speed control 95 system being adapted to control the speed of said prime mover in accordance with the variation of the resistance of said resistance element, an epicyclic gear train to one member of which the prime mover is connected, speed 100 limiting means connected to another member of the gear, and means for varying the pressure on said resistance element including a toggle, a spring tending to actuate said toggle to vary the pressure, and means actuated by a third member of the gear train for controlling said toggle and including a pinion having a yieldable connection with said third member and means for limiting the movement of said pinion. 105 110

5. In speed regulating apparatus, a prime mover, an electrical speed control system for 115 said prime mover including a control circuit and a pressure-controlled variable resistance element in said circuit, said speed control system being adapted to control the speed of said prime mover in accordance with the variation of the resistance of said resistance element, an epicyclic gear train to one member of which the prime mover is connected, speed limiting means connected to another member of the gear, means for varying the pressure on said resistance unit including a yieldable connection with a third member of the gear train, and means for limiting operation of such pressure-varying means. 120 125

6. In speed regulating apparatus, the combination with an electric motor, a motor circuit, an epicyclic gear train to one member of which the prime mover is connected, speed 130

limiting means connected to another member of the gear train, and means for applying a substantially constant torque to a third member of the gear train, of a rheostat, and 6 rheostat-controlling means operable by said third member, the connection between said third member and said rheostat-controlling means being yieldable to prevent damage when the prime mover does not respond quickly enough to the action of the speed control.

7. In speed regulating apparatus, a prime mover, an epicyclic gear train to one member of which the prime mover is connected, 15 speed limiting mechanism connected to another member of the gear train, means for altering the speed of the prime mover, and means actuatable by movement of a third member of the gear train for controlling the 20 speed altering means and including a toggle acting directly on the speed altering means.

8. In speed regulating apparatus, a prime mover, an epicyclic gear train to one member of which the prime mover is connected, 25 speed limiting mechanism connected to an-

other member of the gear train, means for altering the speed of the prime mover and including an actuating member movable with varying resistance in different parts of its path, and means actuatable by a third member 30 of the epicyclic gear train for controlling the speed altering means and adapted to operate said actuating member with a constant torque on said third member.

9. In speed regulating apparatus, a prime 35 mover, an epicyclic gear train to one member of which the prime mover is connected, speed limiting means connected to another member of the gear train, means for altering the speed of the prime mover including a controlling 40 member against which pressure must be exerted in an increasing or decreasing manner to vary the speed of the prime mover, and means actuatable by a third member of the epicyclic gear train and including a toggle 45 acting on said controlling member and adapted to vary the pressure thereon with a constant torque on said third member.

In testimony whereof I affix my signature.
HARRY L. TANNER.
